UNITED STATES PATENT OFFICE.

AUGIE L. HANSEN, OF CHICAGO, ILLINOIS, ASSIGNOR TO JUSTRITE MANUFACTURING COMPANY, OF CHICAGO, ILLINOIS, A CORPORATION OF ILLINOIS.

MULTIPLE CARBID-CONTAINER.

1,137,755.

Specification of Letters Patent.

Patented May 4, 1915.

Application filed April 10, 1914. Serial No. 331,044.

To all whom it may concern:

Be it known that I, AUGIE L. HANSEN, a citizen of the United States, and a resident of Chicago, in the county of Cook and State 5 of Illinois, have invented certain new and useful Improvements in Multiple Carbide-Containers, of which the following is a specification.

My invention relates to an improved multiple carbide container particularly adaptable for use in connection with miners' acetylene lamps.

Miners' lamps must be sufficiently light and small in order that they may be carried 10 as for example on the cap. These lamps usually comprise a water container to which a carbide container is detachably applied. As these lamps must be small and light, the carbide containers cannot be made sufficiently 15 large to carry a charge sufficient for a full working shift. Heretofore miners have carried an extra supply with them and when the lamp became exhausted the carbide container was removed, the contents dumped, 20 and the container recharged. The laws have, however, become very stringent and forbid the dumping of carbide tanks and are also very stringent in connection with the handling of fresh carbide within the mines.

The object of my invention is therefore to 25 provide an improved supply carrier in the form of a multiple container, such container preferably comprising a suitable support for a number of receivers or cover members each 30 of which is adapted to receive a carbide cup or container constructed precisely like the lamp container, that is, the reserve containers are interchangeable with the lamp container.

As the multiple container must be carried 35 by the miner another object is to provide such shape and form that it can be readily carried in the pocket or suspended from the miner's belt.

By reference to the accompanying drawings 40 the various features of the invention will be clearly understood.

In these drawings Figure 1 is a plan view; Fig. 2 is a side elevational view with the 45 central part thereof in vertical diametral section; Fig. 3 is a plan view of a modified form; Fig. 4 is an end view of the form shown in Figs. 1 and 2; and Fig. 5 shows a well known type of lamp whose carbide container, in accordance with the invention, is

interchangeable with any of the multiple container units.

The holder or support for the multiple container may be, as shown in Figs. 1 and 2, in the form of a top plate 10 having depending sides 11 and 12. Riveted to the top and held between the sides 11 and 12 are the receiving members 13 each in the form of a cap whose side 14 is threaded and from which depends a gasket skirt 15. The threaded side and skirt of each receiver is of substantially the same construction as the receiving end 16 of an acetylene lamp such as shown in Fig. 5. In other words, the lamp carbide container 17 may be inserted in 50 any of the receivers 13 in the same manner in which it is inserted in the lamp. Each of the caps 13 of the multiple container receives a reserve container 18 constructed exactly like the lamp container 17, comprising 55 the body 19, the threaded neck 20 and the conical gasket shoulder 21 between which and the skirt 15 of the respective receiver is interposed a gasket 22 usually of rubber. The units of the multiple container are preferably arranged in a row as shown, so that 60 the entire structure can be readily slipped into the pocket. A hook 23 may be provided by means of which the structure can be readily suspended from the miner's belt. 65 Before the miner starts for work he fills the reserve containers 18 and screws them tightly into the receivers, and he also fills the lamp carbide container. Then, as soon as 70 the carbide in the lamp container is exhausted 75 he unscrews this container and one of the reserve containers and interchanges them without dumping the exhausted container, and he can run a full shift on the supply carried in the lamp container and the reserve 80 containers. A vent hole 24 is preferably provided through the top 10 and through 85 each receiver through which vent any gases may escape which might still remain in the containers after they are taken from the 90 lamp and applied to the receiver.

In Fig. 3 I have shown a modified arrangement, the holder for the receivers instead of being formed of sheet metal as shown in Fig. 2, is in the form of a wire 105 frame 25 bent to intimately receive each receiver, and the frame may be bent up at one end to form a belt hook 26. The vents 27 in the caps will allow escape of any gases. In either form of structure the receiving 110

caps may of course be additionally secured by the use of solder or otherwise.

I thus provide a multiple container by means of which a container full of fresh carbid may be quickly substituted for the spent container without need of dumping the exhausted container. The multiple container structure is of such shape as to be readily carried in the pocket or to be conveniently 10 suspended from a support such as a belt.

I do not of course desire to be limited to the exact construction and arrangement shown and described, as changes are no doubt possible which would still come within 15 in the scope of the invention.

I claim the following:

1. In a multiple carbid container, the combination of an elongated supporting frame, a plurality of receivers secured in a row to 20 said frame, and a carbide receptacle detachably secured in each receiver, and each adapted for interchangeability with the carbide receptacle of an acetylene lamp.

2. In a multiple container, the combination of an elongated supporting frame, a 25 plurality of threaded caps secured to the

frame and arranged in a row, a plurality of receptacles each having a threaded neck for detachable engagement with one of said caps, and a belt hook forming an integral 30 part of the supporting frame.

3. In a multiple container, the combination of a supporting frame, a plurality of caps secured to the frame, and each adapted to detachably receive a carbide receptacle, 35 each cap having a vent opening through which gases may escape from the receptacle held thereby.

4. In a multiple carbid container, the combination of a supporting frame, a plurality 40 of threaded caps secured to said frame and each adapted to receive an acetylene lamp carbide receptacle, each cap having a vent opening for the escape of gases from the receptacle held thereby, and a belt hook on 45 the supporting frame.

In witness whereof, I hereunto subscribe my name this 8th day of April, A. D. 1914.

AUGIE L. HANSEN.
